United States Patent Office

Des. 198,150
Patented May 5, 1964

198,150

COMBINED DISPLAY AND DISPENSING STAND

Ole Hibner, % Hibner Products, Inc.,
2526 Detroit Ave., Cleveland, Ohio

Filed Feb. 26, 1963, Ser. No. 73,728

Term of patent 7 years

(Cl. D80—9)

FIG. 1 is a perspective view of a combined display and dispensing stand showing my new design;

FIG. 2 is a left side elevation thereof;

FIG. 3 is a top plan view thereof showing a top cover portion in open position.

I claim:

The ornamental design for a combined display and dispensing stand, as shown.
